Continuation-in-part of design application Ser. No.
316,852, Dec. 20, 1973, which is a continuation-in-
part of design application Ser. No. 316,882, Dec.
20, 1972, both now abandoned. This application
Aug. 3, 1973, Ser. No. 385,606

Term of patent 14 years

Int. Cl. D7—02

U.S. Cl. D7—128

FIG. 1

FIG. 2

FIG. 1 shows a front perspective view of the present invention with a window formed in the oven door where the window is recessed and surrounded by a darkened shadow-box frame of rectangular form that merges into a similarly darkened control panel at one side of the door. An integral door handle is likewise darkened, and is located along one side edge of the door adjacent the control panel. The drawing is shaded to indicate color contrast.

FIG. 2 is a perspective view of a modification of the present invention where the oven is of the same configuration as in FIG. 1 except that the drawing has been shaded in the reverse manner at the front portion of the oven to indicate a reverse color contrast.

The right side wall of the oven that is not shown is substantially like the left side that is shown and the bottom wall and back wall are flat and substantial.

ly plain. The characteristic feature of our invention resides in the specific configuration and appearance of the front portion of the oven.

This is a continuation-in-part application of applicants' two copending applications Ser. Nos. 316,852 and 316,882, both filed Dec. 20, 1973, and now abandoned.

We claim:

The ornamental design for a portable microwave oven or similar article, as shown and described.
